Primary Examiner — Patricia A Palasik*(74) Attorney, Agent, or Firm* — Dykema Gossett PLLC(57) **CLAIM**

The ornamental design for a linear actuator accessory, as shown and described.

DESCRIPTION

FIG. 1 is a perspective top view of a linear actuator accessory showing my new and ornamental design,
FIG. 2 is a perspective bottom view thereof,
FIG. 3 is a top plan view thereof,
FIG. 4 is an elevational left side view thereof,
FIG. 5 is an elevational right side view thereof,
FIG. 6 is a bottom plan view thereof,
FIG. 7 is an elevational front view thereof; and,
FIG. 8 is an elevational rear view thereof.

1 Claim, 2 Drawing Sheets(56)
